MERCURY CATHODE DISCHARGE TUBE

Tom Jurriaanse, Eindhoven, Netherlands, assignor to N. V. Philips' Gloeilampenfabrieken, Eindhoven, Netherlands

Application April 15, 1938, Serial No. 202,333
In Germany April 10, 1937

8 Claims. (Cl. 175—354)

My invention relates to mercury-cathode discharge tubes, and more particularly to means for controlling the main discharge in such tubes.

It has been proposed to block the main discharge by applying a negative potential to an electrode located within the discharge space or to a metallic member forming part of the envelope of the tube. This method, however, is comparatively uncertain and it is difficult to 10 make it sufficiently reliable for practical use.

The main object of my invention is to overcome this difficulty, and for this purpose I locate an extinguishing electrode in the immediate vicinity of the cathode spot, and apply thereto 15 a potential which is positive with respect to the cathode to thereby take over the discharge from the main anode. By locating the extinguishing electrode in the immediate vicinity of the cathode spot, its influence on the portion of the main 20 discharge near the cathode, is considerably greater than that of the anode, and as a result the extinguishment will always be effectuated with great reliability and under constant conditions.

25 To ensure conditions which are favorable for extinguishment of the discharge, I prefer to provide a cathode-spot anchoring body. However, these conditions can also be attained without using an anchoring body, by reforming the cathode spot during each current impulse. As a result, and because of the short duration of each impulse, the cathode spot can, during the passage of current, move only a short distance from the point at which it is produced. This means that 30 irregularities in the effect exerted by the extinguishing electrode on the cathode spot—in so far as they may be due to variations in the location of the spot—are practically eliminated. For this purpose I may use an internal ignition electrode 35 of semi-conductive material, i. e. an "igniter", which is permanently immersed in the cathode mercury, and which at the start of each current impulse forms the cathode spot anew at the point of immersion.

40 A combination of an extinguishing device according to the invention and the above-described internal ignition electrode may be obtained in a simple manner by using a single auxiliary electrode consisting of a conductive portion arranged 45 in the immediate vicinity of the cathode mercury, and a semi-conductive portion immersed in the mercury and acting as the internal ignition electrode. This greatly simplifies the construction of the tube because only a single electrode and 50 current-supply conductors serve both for extin- 55

guishing the discharge and forming the cathode spot.

In such a device a cathode spot is formed each time at the point of immersion but does not attain the required intensity before the semi-conductive portion has been bridged by the discharge which climbs up to the upper conductive portion. Owing to its low resistance, the conductive upper portion forms the portion of the auxiliary electrode which is essential for the extinguishing impulse with its very high current intensity of short duration, and therefore, in accordance with the invention, this portion must be arranged in the immediate vicinity of the anchoring point of immersion. Thus, I prefer to extend the conductive portion, which acts as a holder and as a current-supply conductor for the semi-conductive portion, along the side of the latter portion and coaxially to the same so that it will extend into the immediate vicinity of the cathode mercury. 10 15 20

In the extinguishing process according to the invention, it can be assumed that when a short positive voltage impulse is applied to the auxiliary or extinguishing electrode, the discharge passes 25 in an extremely short time from the main anode to the extinguishing electrode, and that this discharge must be extinguished at once at this electrode, to prevent it from returning to the main anode immediately after the positive voltage impulse. 30 The first part of this process may therefore be improved by making the wave front of the positive voltage applied to the auxiliary electrode as steep as possible, and for this purpose I prefer to apply, by way of a mechanical contact 35 or a controlled gas filled discharge device, a potential obtained from the terminal of a charged condenser, which terminal is positive with respect to the cathode of the tube.

During the second part of the process, i. e. the 40 subsequent extinguishment of the discharge after its shifting to the auxiliary electrode, possibly a favorable influence is exerted by the extinguishing electrode becoming negative during a short 45 moment following the positive voltage impulse. This may result from oscillations in the extinguishing circuit, for example, due to resonance with the condenser utilized. It is therefore desirable to give the extinguishing circuit a very 50 low resistance, because otherwise, due to the extremely heavy current which is produced during a short time, the greater part of the voltage would be dissipated in this circuit. For this purpose, I prefer to keep the resistance of the extin- 55

guishing circuit at a low value for instance below 0.1 ohm.

In order that the invention may be clearly understood and readily carried into effect I shall describe the same in more detail with reference to the accompanying drawing in which:

Fig. 1 is a schematic diagram of a direct current extinguished device according to the invention, and

Fig. 2 is a schematic diagram of a device according to the invention in which the mean value of the direct current in a rectifier is regulated.

The device illustrated in Figure 1 comprises a mercury-cathode discharge tube having an envelope 1, a main anode 4, a mercury cathode 2, and a cathode-spot anchoring member 3 for instance of nickel. Partly immersed in mercury 2 is a stationary internal ignition electrode or igniter 5 of a semi-conductive substance such as silicon carbide. Above the member 3 is a cup-shaped extinguishing electrode 6, for instance of iron or molybdenum, whose side extends downwardly with its edge in the vicinity of and concentrically to the cathode line formed around the periphery of member 3. In this manner, the entire cathode line can be influenced in the same way.

Anode 4 is connected through a load 8, shown as an ohmic resistance, to the positive terminal 30 of a direct-current supply 7, shown as a generator, whose negative terminal is connected to cathode 2.

Electrode 5 is connected through a single-pole single-throw switch 10 and a current-limiting resistance 9 to the positive terminal of supply 7. Closure of switch 10 applies a positive potential to electrode 5 to thereby initiate the main discharge in a manner which is known per se.

The positive terminal of supply 7 is also connected through a conductor 31, to a contact 26 of a single-pole double throw switch 12 having a second contact 27 connected through a conductor 34 to the extinguishing electrode 6. The heel 28 of switch 12 is connected through a conductor 35 to terminal 29 of a condenser 11 whose other terminal 30 is connected through a conductor 36 to cathode 2 and to the negative terminal of source 7. With switch 12 in the position shown, condenser 11 becomes charged from source 7 to make terminal 29 positive, and when switch 12 is moved in the direction of the arrow so as to break contact 26 and make contact 27, electrode 29 is connected to electrode 6. Condenser 11, then discharges through the short discharge path between electrode 6 and mercury 2 with the result that the main discharge is transferred from main anode 4 to electrode 6 and is extinguished at the first change in polarity of the voltage of oscillatively-discharging condenser 11.

As has been stated it is advisable to make the discharge circuit of condenser 11 of low resistance to ensure that the discharge oscillations will be as strong as possible and for this purpose conductors 34, 35, and 36 are made short and of large cross-sections, as indicated by heavy lines.

I have found that the highest current which can be extinguished by a device such as shown in Fig. 1 is substantially directly proportional to the direct voltage applied to condenser 11, i. e. to the root of the stored energy $1/2 CV^2$. If it is desired to increase the amount of current which can be extinguished, an additional source of direct current may be inserted in conductor 31 so as to charge condenser 11 to a higher voltage. I have found that when source 7 had a value of about

130 volts, and condenser 11 had a capacity of about 10 microfarads, it was possible to extinguish a main anode current of 5 amperes with a condenser voltage of 230 volts, and a current of 10 amperes with a condenser voltage of 460 volts. 5

In Fig. 2, in which similar parts are given the same reference numerals as in Fig. 1, the main anode 4 is connected through load 8 to one terminal 37 of an A. C. supply 13, shown as a generator, whose other terminal 38 is connected to 10 cathode 2.

In this case an internal ignition electrode 14, of semi-conducting material which is similar to electrode 5 of Figure 1, is partly immersed in the cathode 2 and is secured to a holder 15 of a conductive material, for instance iron or molybdenum. The holder 15 also serves as an extinguishing electrode and for this purpose is provided with a flared lower edge 39 which extends close and concentrically to the circular limiting 20 line of electrode 14 and mercury 2. Electrode 14-15 is provided with a common terminal 40.

A transformer 16 has a primary winding 32 connected through conductors 33 and 34 to terminals 37 and 38 respectively, and has two secondary windings 17 and 18 which serve to charge two condensers 21 and 22. For this purpose winding 17 has one end connected, through a rectifier 19, which may be a dry or thermionic rectifier, to one terminal of condenser 21 and its other end 30 connected to the other terminal of this condenser. Similarly, winding 18 has one end connected through a rectifier 20 to one terminal of condenser 22 and its other end connected to the other terminal of this condenser. 35

The discharge of condensers 21 and 22 is controlled by two commutators 23 and 24 mounted on the shaft of a synchronous motor 25 connected across A. C. supply 13. Commutator 23 periodically inter-connects contacts 41 and 42 40 connected to condenser 21 and terminal 40 respectively, and commutator 24 periodically inter-connects contacts 43 and 44 connected to condenser 22 and terminal 40 respectively. In this manner condensers 21 and 22 are discharged at 45 the proper instant through electrode 14-15. It will be noted that, as in Fig. 1, the discharge circuit of condenser 21 is given a low resistance as indicated by heavy lines.

The windings 17 and 18, as well as rectifiers 50 19 and 20, are so arranged that the terminals of the condensers connected to contacts 41 and 43 will be positively charged as indicated, and that the charging will take place during the blocking phase of the discharge tube. Thus it is possible to first apply one positive voltage impulse to terminal 40 by means of commutator 24 and subsequently apply a second positive voltage impulse with commutator 23. In this manner it is possible to control the mean value of the rectified 55 current and to select at will within certain limits the phase of the current impulses with respect to the voltages.

It will be noted that fixed contacts 41 and 42 and fixed contacts 43 and 44 are mounted on 65 insulating rings 45 and 46 which are provided with an angular adjustment in the direction of the double-headed arrows. In this way it is possible to adjust the sequence of and the interval between the closure of contacts 41-42 and contacts 43-44 by way of the commutators 23 and 24 respectively. 70

As shown in the drawing, the commutators 23 and 24 are positioned in a current-carrying phase of the discharge tube. Commutator 24 has just 75

bridged contacts 43 and 44 to apply the positive voltage of condenser 22 to terminal 40 and thereby initiate the main discharge. The main discharge is taking place, and when commutator 23 connects contacts 41 and 42, the positive potential of condenser 21 will be applied to terminal 40 to interrupt the discharge.

After each ignition at the semi-conductive portion 14, it is impossible for the cathode spot 10 formed at this point to move any appreciable distance away in the short interval before application of the positive potential to portion 15. As a result the extinguishment of the discharge is effected in a very reliable and regular manner.

15 It will be noted that the single electrode 14-15 has two distinct functions, i. e. forming a cathode spot and interrupting the main discharge, which are effected in a similar manner and with similar switching means.

20 In preliminary experiments on a device such as shown in Fig. 2, I found that it was possible to reduce a rectified current having a mean value of 1.5 amperes and with an effective voltage of the A. C. supply 13 of 220 volts, to a mean value 25 of 0.5 ampere without the need of delaying the establishment of the discharge. In this case condenser 21 was given a capacity of 6 microfarads and winding 18 produced an effective voltage of 600 volts. However, with some forms of construction this voltage can be reduced an appreciable amount.

While I have described my invention in connection with specific examples and applications, I do not wish to be limited thereto, but desire the 35 appended claims to be construed as broadly as permissible in view of the prior art.

What I claim is:

1. A current-converting installation comprising a discharge tube having a mercury cathode, a 40 main anode spaced from said cathode to form a discharge space, means to form a cathode spot on said mercury cathode, and an extinguishing electrode above the surface of said mercury cathode and adjacent the cathode spot formed thereon, and means for applying to said electrode, to interrupt the main discharge, a short voltage impulse which is positive with respect to the cathode.

2. A current-converting installation comprising a discharge tube having a mercury cathode, a main anode spaced from said mercury to form a discharge space, a cathode-spot anchoring member partly within said mercury, means to form a cathode spot on said mercury cathode, and an extinguishing electrode above the surface of the mercury and adjacent said member, and means for applying to said electrode, to interrupt the main discharge, a short voltage impulse which is positive with respect to the cathode.

3. A current-converting installation comprising a discharge tube having a mercury cathode, a main anode spaced from said cathode to form a discharge space, an internal ignition electrode permanently immersed in the mercury, and an extinguishing electrode above the surface of said mercury cathode and adjacent the cathode spot formed thereon, and means for applying to said electrode, to interrupt the main discharge, a short

voltage impulse which is positive with respect to the cathode.

4. A current-converting installation comprising a discharge tube having a mercury cathode, a main anode spaced from said mercury to form a discharge space, a body having a semi-conductive portion permanently immersed in the mercury and serving as an internal ignition electrode, and a conductive portion above the surface of the mercury and adjacent thereto, said latter portion 10 serving as an extinguishing electrode, and means for applying to said body to interrupt the main discharge, a short voltage impulse which is positive with respect to the cathode.

5. A current-converting installation comprising a discharge tube having a mercury cathode, a main anode spaced from said cathode to form a discharge space, and a body having a portion of conductive material disposed above the surface of the mercury, and a semi-conductive portion 20 supported by said first portion and extending into the mercury to act as an internal ignition electrode, said first portion extending along the sides of the second portion to the immediate vicinity of the mercury surface, and means including a 25 single conductor connected to said first portion to supply current to said second portion and to apply to said first portion a short voltage impulse which is positive with respect to the cathode to thereby interrupt the main discharge. 30

6. A current-converting installation comprising a discharge tube having a mercury cathode, a main anode spaced from said cathode to form a discharge space, an extinguishing electrode above the surface of said mercury cathode and adjacent 35 the cathode spot formed thereon, and means for applying to said electrode, to interrupt the main discharge, a short voltage impulse which is positive with respect to the cathode and has a steep front. 40

7. A current-converting installation comprising a discharge tube having a mercury cathode, a main anode spaced from said mercury to form a discharge space, and an extinguishing electrode above the surface of the mercury and adjacent 45 the cathode spot formed thereon, and means for applying to said electrode, to interrupt the main discharge, a short voltage impulse which is positive with respect to the cathode, said means comprising a condenser having a terminal adapted to 50 be connected to said extinguishing electrode, and a voltage supply source for charging the condenser.

8. A current-converting installation comprising a discharge tube having a mercury cathode, a 55 main anode spaced from said cathode to form a discharge space, an igniting electrode, and an extinguishing electrode above the surface of the mercury and adjacent the point at which the cathode spot is formed during operation of the 60 tube, and means for applying to said electrode to interrupt the main discharge a short current impulse which is positive with respect to the cathode, said means including an extinguishing circuit, and a source of voltage within said circuit, 65 the resistance of the circuit being less than 0.1 ohm.

TOM JURRIAANSE.
